UNITED STATES PATENT OFFICE.

NORMAN A. CARBERY, OF CHICAGO, ILLINOIS.

DESIGN FOR A STATUETTE.

43,103.

Specification for Design.

Patented Oct. 8, 1912.

Application filed July 13, 1912. Serial No. 709,297. Term of patent 7 years.

To all whom it may concern:

Be it known that I, NORMAN A. CARBERY, a citizen of the United States, residing at Chicago, in the county of Cook and State of Illinois, have invented a new, original, and ornamental Design for a Statuette, of which the following is a specification, reference being had to the accompanying drawing, forming part thereof.

The drawing shows the design in perspective.

I claim:

The ornamental design for a statuette as shown.

In witness whereof, I have hereunto subscribed my name in the presence of two witnesses this tenth day of July 1912.

NORMAN A. CARBERY.

Witnesses:

LILLIAN D. SMITH,
IRWIN N. WALKER.
